Fig. 1.

FIG. 1 is a front view of the seat, showing our new design;

FIG. 2 is a side elevational view of the seat shown in FIG. 1;

FIG. 3 is a rear elevational view of the seat shown in FIG. 1;

FIG. 4 is a frontal perspective view showing our new design; and

FIG. 5 is a view similar to that of FIG. 2, but with the seat turned somewhat more to the observer, and with the seat being shown on an enlarged scale.

The design is characterized by the bighted tubular member along the side of the chair back in combination with the bifurcated cushion elements all as best illustrated in FIG. 5.

We claim:

The ornamental design for a seat, substantially as shown and described.
